CLAIM

The ornamental design for a smart camera, as shown and described.

DESCRIPTION

FIG. 1 is a top, front and right side perspective view of a smart camera showing my new design;

FIG. 2 is a bottom, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and, FIG. 10 is a top, front and right side perspective view showing the smart camera in a state of use.

The evenly dashed broken lines in the drawings illustrate the portions of the smart camera which form no part of the claimed design. The unevenly dashed broken lines in FIGS. 1 and 9 demarcate the area shown in the enlarged view in FIG. 9 and form no part of the claimed design.

The oblique shade lines in the drawings represent a reflective surface.
